UNITED STATES PATENT OFFICE.

FINLY F. JOSEPH, OF GRAND RAPIDS, MICHIGAN.

HOISTING APPARATUS.

No. 911,883.

Specification of Letters Patent.

Patented Feb. 9, 1909.

Application filed June 8, 1908. Serial No. 436,430.

To all whom it may concern:

Be it known that I, FINLY F. JOSEPH, a citizen of the United States, residing at Grand Rapids, Michigan, have invented certain new and useful Improvements in Hoisting Apparatus, of which the following is a specification.

This invention relates to improvements in hoisting apparatus.

10 My improved hoisting apparatus is especially adapted and designed by me for use as a coaling station, or coal loading device for cars, and I have shown it so adapted in the accompanying drawings, although it can 15 be readily adapted for use in various other relations.

The main objects of this invention are: First, to provide an improved hoisting apparatus in which the buckets are automatically charged. Second, to provide an improved hoisting apparatus in which the buckets are automatically discharged.

20 Further objects, and objects relating to structural details, will definitely appear 25 from the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which:

30 Figure 1 is a detail vertical section of an apparatus embodying the features of my invention, the bucket and its hoisting cable and the discharge chute being shown in full lines, the bucket being shown in its charging position. Fig. 2 is a detail side elevation, showing the bucket in its discharging position, the open position of the bottom of the bucket being indicated by dotted lines. Fig. 3 is an enlarged detail side elevation, 35 with one end wall of the hoppers removed, showing the arrangement of the charge hopper doors and their connections. Fig. 4 is a 40 horizontal section taken on a line corresponding to line 4-4 of Fig. 2, looking in the direction of the little arrows at the end of the section lines, the bucket being in its discharging position.

In the drawings, similar reference numerals refer to similar parts throughout the 45 several views.

It is desired to remark that in the accompanying drawings, the parts are shown illustrative only and no attempt has been made to maintain their proper proportions, although the relation of the parts are clearly 60 illustrated.

Referring to the drawing, the hoist shaft 1 is preferably made up of suitable timbers connected by cross pieces, and provided with a roof, as 2. Suitable ways 3 are provided 65 for the hoist bucket 4. The cable 5 is arranged over a suitable pulley 6 in the top of the shaft.

In practice, I preferably employ two buckets connected to be alternately operated, 70 but as this arrangement will be well understood, and as a description of one will clearly disclose my invention, I do not illustrate the second bucket herein.

At one side of the elevator shaft, I provide a supply hopper 7, the track 31 being laid across it so that the coal may be dumped into the hopper from a car, if desired. This track is also so positioned that a car to be loaded may be run into position thereon. 75 The charge hopper 8 is located at one side of the supply hopper to receive the coal therefrom. The bottoms 9 of the hoppers are preferably inclined and in the same plane so that the coal runs freely from the supply hopper into the charge hopper. The charge hopper is provided with an inlet door 10, which is arranged to reciprocate vertically through the bottom 9. The supply 80 hopper is provided with a discharge door 11, which is also vertically movable. These doors are connected, preferably, by means of cables 12 and 13, which are arranged over guide rollers 14, see Fig. 3, arranged above and below the same so that when one door is 85 opened, the other is closed, thus permitting the charge hopper 8 to either fill or discharge accordingly as the inlet or discharge door is opened or closed.

The discharge door 11 is provided with an arm 15, which projects into the shaft to be engaged by the bucket 4 on its downward movement, so that the discharge door is opened by the bucket and the inlet door closed. On the upper end of the discharge 100 door I pivot an apron-like chute 16, adapted, when in its extended position, to deliver into the bucket, see Fig. 1. The door 11 is so arranged that its upper edge is in alignment with the bottom of the charge hopper 110

8 so that the coal runs from the bottom into the bucket over the chute. On the hoisting movement of the bucket, it closes the discharge door 11 and opens the inlet door 10.

5 The chute 16 serves as a connection for the bucket to the door for closing the door. When the door is opened, or partially opened, the counterweight 17, which is rigidly connected to swing with the door, bears 10 against the way 18 for the door acting like an arm to prevent the closing movement of the door on its pivot so that the bucket engages the chute and lifts the door 11. When the door is in its closed position, the ways 15 18 are of such length that the counterweight can swing over the upper end thereof, thus allowing the chute to swing out of the way and retain it in the position indicated by dotted lines in Fig. 3, until the bucket again 20 moves downwardly engaging the projection 15 thereon and carrying the door downward. As the counterweight is fulcrumed over the ends of the ways 18, this downward movement swings the counterweight upward and 25 the chute into its delivery or extended position, as appears in Fig. 1, and the counterweight, being rigidly connected to the door, as previously stated, and bearing against the way 18, the chute is held in its extended 30 position.

I thus secure, in a simple and effective manner, means by which the bucket is automatically charged with a fixed quantity of material. I also preferably use, in this connection, means for automatically discharging the bucket. To accomplish this, I provide the bucket with a hinged bottom 19, which is held in its closed position by the pivoted latch 20 adapted to engage over 40 the keeper 21 on the bottom of the bucket. The latch is held yieldingly in its engaging position by the spring 22. A reciprocating trip 23 is mounted on the bottom to engage the latch and release the bottom. This trip 45 is mounted on suitable guides, as 24, and is arranged to engage the cam-shaped trip member 25 when the bucket reaches its discharging position, thus releasing the bottom, allowing it to drop down to discharge the 50 load. The discharge chute, or spout 26, is mounted on the pivot rod 27 and is adapted to swing up to receive the bottom 19, as clearly appears in Fig. 2, the end of the chute swinging out of the elevator shaft to 55 discharge into the conduit 32.

To automatically swing and retain the chute 26 in position, I provide the same with a bail 28 which is engaged by the bucket, thereby lifting the chute into position to 60 receive the load and support it and the bottom at the same time allowing it to swing down out of the way on the downward movement of the bucket. The cross-piece 29 of the bail is extended at each end to engage 65 the end ways 30, see Figs. 2 and 4, so that

the bail is held in position to be engaged by the bucket. By these means, in a simple and effective manner, the parts are automatically brought into their discharging position and discharge the load so that the 70 entire operation of charging and discharging of the bucket is automatic. I have not shown, herein, the power means for hoisting the bucket, as such means will be readily understood by those skilled in the art to 75 which this invention relates.

I have illustrated and described my improved hoisting apparatus in detail in the form preferred by me on account of its structural simplicity and economy of operation. I am aware, however, that it is capable of considerable variation without departing from my invention, and I desire to be understood as claiming the same specifically, as illustrated, as well as broadly. 80 85

Having thus described my invention, what I claim as new and desire to secure by Letters Patent, is:

1. The combination with a hoisting bucket; of a supply hopper; a charge hopper to which said supply hopper is arranged to deliver, said hoppers having inclined bottoms; a vertically sliding inlet door for said charge hopper arranged to reciprocate through the floor of the hoppers; a vertically sliding discharge door for said charge hopper; a connecting cable for the upper and lower ends of said inlet and discharge doors; guide rollers for said cables arranged so that when one door is opened the other is closed; an arm on said discharge door adapted to be engaged by said bucket as it descends, whereby said discharge door is opened and said inlet door is closed; a chute pivoted on the upper end of said discharge door adapted, when opened, to extend into said bucket; a counterweight for said chute; and a way for said discharge door adapted to engage said counterweight on the opening movement of said door whereby said chute is thrown into its extended position and held in engagement with said bucket so that on its hoisting movement said discharge door is closed, said counterweight being adapted to swing over the upper end of said way and close said chute and release said discharge door when said discharge door reaches its closed position. 110 115

2. The combination with a hoisting bucket of a supply hopper; a charge hopper to which said supply hopper is arranged to deliver; a vertically sliding inlet door for said charge hopper; a vertically sliding discharge door for said charge hopper; a connecting cable for the upper and lower ends of said inlet and discharge doors; guide rollers for said cables arranged so that when one door is opened the other is closed; an arm on said discharge door adapted to be engaged by said bucket as it descends, 120 125 130

- whereby said discharge door is opened and said inlet door is closed; a chute pivoted on the upper end of said discharging door adapted, when opened, to extend into said bucket; a counterweight for said chute; and a way for said discharge door adapted to engage said counterweight on the opening movement of said door whereby said chute is thrown into its extended position and held in engagement with said bucket so that on its hoisting movement said discharge door is closed, said counterweight being adapted to swing over the upper end of said way and close said chute and release said discharge door when said discharge door reaches its closed position.
3. The combination with a hoisting bucket; a supply hopper; a charge hopper to which said supply hopper is arranged to deliver; a vertically sliding inlet door for said charge hopper; a vertically sliding discharge door for said charge hopper; connections for said doors whereby when one door is opened the other is closed, said bucket being arranged to engage said discharge door as it descends, whereby said discharge door is opened and said inlet door is closed; a chute pivoted on the upper end of said discharge door adapted, when opened, to extend into said bucket; a counterweight for said chute; and a way for said discharge door adapted to engage said counterweight on the opening movement of said door whereby said chute is thrown into its extended position and held in engagement with said bucket so that said discharge door is closed on the hoisting movement of the bucket, said counterweight being adapted to swing over the upper end of said way to close said chute and release said discharge door when said discharge door reaches its closed position.
4. The combination with a hoisting bucket; a supply hopper; a charge hopper to which said supply hopper is arranged to deliver; a vertically sliding inlet door for said charge hopper; a vertically sliding discharge door for said charge hopper; connections for said doors whereby when one door is opened the other is closed, said bucket being arranged to engage said discharge door as it descends, whereby said discharge door is opened and said inlet door is closed; a chute pivoted on the upper end of said discharge door adapted, when opened, to extend into said bucket; a counterweight for said chute; and a way adapted to engage said counterweight on the opening movement of said door whereby said chute is thrown into its extended position and held in engagement with said bucket so that said discharge door is closed on the hoisting movement of the bucket, said counterweight being adapted to swing over the upper end of said way to close said chute and release said discharge door when said discharge door reaches its closed position.
5. The combination with a hoisting bucket; a charge hopper; a vertically sliding discharge door for said charge hopper; a chute pivoted on the upper end of said discharge door adapted, when opened, to extend into said bucket; a counterweight for said chute; and a way for said discharge door adapted to engage said counterweight on the opening movement of said door so that said chute is thrown into its extended position and held in engagement with said bucket, thereby closing said discharge door on the hoisting of the bucket, said counterweight being adapted to swing over the upper end of said way to close said chute and release said discharge door when said discharge door reaches its closed position.
6. The combination with a hoisting bucket; a charge hopper; a vertically sliding discharge door for said charge hopper; a chute pivoted on the upper end of said discharge door adapted, when opened, to extend into said bucket; a counterweight for said chute; and a way adapted to engage said counterweight on the opening movement of said door so that said chute is thrown into its extended position and held in engagement with said bucket, thereby closing said discharge door on the hoisting of the bucket, said counterweight being adapted to swing over the upper end of said way to close said chute and release said discharge door when said discharge door reaches its closed position.
7. The combination with a hoisting bucket; a supply hopper; a charge hopper to which said supply hopper is arranged to deliver; a vertically sliding inlet door for said charge hopper; a vertically sliding discharge door for said hopper; connections for said doors whereby when one door is opened the other is closed, said bucket being arranged to engage said discharge door as it descends, thereby opening said discharge door and closing said inlet door; a chute pivoted on the upper end of said discharge door adapted, when extended, to deliver to said bucket; and means for extending said chute and retaining it in its extended position during the opening and closing movement of the discharge door, said chute engaging said bucket so that said door is closed on the hoisting movement of the bucket.
8. The combination with a hoisting bucket; a hopper; a vertically sliding discharge door for said hopper; a chute pivoted on the upper end of said discharge door adapted, when extended, to deliver to said bucket; and means for extending said chute and retaining it in its extended position during the opening and closing move-

- ment of the discharge door, said chute engaging said bucket so that said door is closed on the hoisting movement of the bucket.
9. The combination with a hoisting bucket; a supply hopper; a charge hopper to which said supply hopper is arranged to deliver; an inlet door for said charge hopper; a discharge door for said charge hopper; connections for said doors whereby when one door is opened the other is closed; a chute pivoted on the upper end of said discharge door adapted, when extended, to deliver to said bucket; means for extending said chute and retaining it in its extended position during the opening movement of the discharge door; and means for connecting said bucket to said doors whereby they are actuated thereby.
10. The combination with a hoisting bucket; a supply hopper; a charge hopper to which said supply hopper is arranged to deliver; an inlet door for said charge hopper; a discharge door for said charge hopper; connections for said doors whereby when one door is opened the other is closed; a chute arranged to be automatically extended to deliver to said bucket when said discharge door is opened; and means for connecting said bucket to said doors whereby they are actuated thereby.
11. The combination with a hoisting bucket; a supply hopper; a charge hopper to which said supply hopper is arranged to deliver; an inlet door for said charge hopper; a discharge door for said charge hopper; connections for said doors whereby when one door is opened the other is closed; and means for connecting said bucket to said doors whereby they are actuated thereby.
12. The combination with a hoisting bucket; a hopper; a discharge door for said hopper; a chute pivoted on the upper end of said discharge door adapted, when extended, to deliver to said bucket; means for extending said chute and retaining it in its extended position during the opening movement of the discharge door; and means for connecting said bucket to said door whereby it is opened and closed thereby.
13. The combination with a hoisting bucket; a hopper; a discharge door for said hopper; a chute arranged to be automatically extended by the movement of said bucket to deliver to said bucket when said discharge door is opened; and means for connecting said bucket to said door whereby it is opened and closed thereby.
14. The combination with a hoisting bucket; a supply hopper; a charge hopper to which said supply hopper is arranged to deliver; an inlet door for said charge hopper; a discharge door for said charge hopper; connections for said doors whereby when one
- door is opened the other is closed; a chute; means for automatically extending said chute; and means for automatically opening and closing said doors on the lowering and hoisting of said bucket.
15. The combination with a hoisting bucket; a supply hopper; a charge hopper to which said supply hopper is arranged to deliver; an inlet door for said charge hopper; a discharge door for said charge hopper; connections for said doors whereby when one door is opened the other is closed; and means for automatically opening and closing said doors on the lowering and hoisting of said bucket.
16. In a structure of the class described, the combination with a shaft, of a bucket having a hinged bottom; a latch for said bottom; ways for said bucket; a pivotally-supported discharge spout; a bail pivoted on said discharge spout, adapted to be engaged by the bucket when in its discharging position, whereby said discharge spout is swung into and supported in its discharging position, and in position to receive and support the bottom of the bucket; guide ways for the upper end of said bail; and a trip adapted to disengage said latch for said bucket bottom when said bucket is in its discharging position.
17. In a structure of the class described, the combination with a shaft, of a bucket having a hinged bottom; a latch for said bottom; ways for said bucket; a pivotally-supported discharge spout; a bail pivoted on said discharge spout, adapted to be engaged by the bucket when in its discharging position, whereby said discharge spout is swung into and supported in its discharging position, and in position to receive and support the bottom of the bucket; and a trip adapted to disengage said latch for said bucket bottom when said bucket is in its discharging position.
18. In a structure of the class described, the combination with a shaft of a hoisting bucket; a pivotally-supported discharge spout; a bail pivoted on said discharge spout, adapted to be engaged by the bucket when in its discharging position, whereby said discharge spout is swung into position to receive the contents of the bucket; and guide ways for the upper end of said bail, said bail being provided with projections arranged to travel in said ways.

In witness whereof, I have hereunto set my hand and seal in the presence of two witnesses.

FINLY F. JOSEPH. [L. s.]
